UNITED STATES PATENT OFFICE.

ROBERT V. BINGAY, OF PITTSBURGH, PENNSYLVANIA, ASSIGNOR TO PITTSBURGH TRANSFORMER COMPANY, A CORPORATION OF PENNSYLVANIA.

TRANSFORMER-TANK COVER.

Application filed August 10, 1920. Serial No. 402,568.

To all whom it may concern:

Be it known that I, ROBERT V. BINGAY, a citizen of the United States, residing at Pittsburgh, in the county of Allegheny and State of Pennsylvania, have invented certain new and useful Improvements in Transformer-Tank Covers, of which the following is a specification.

This invention relates to tanks for electric 10 transformers of the oil cooled type and particularly to a cover for such a tank. The chief object of the invention is to provide a flexible cover of sheet steel, preferably steel, which will be inexpensive to form and of 15 great strength.

Further objects of the invention in crowning the top and providing it with openings to the interior of the tank will appear from the following description taken in connection with the accompanying drawings, in which—

Figs. 1, 2 and 3 are diagrammatic views illustrating the formation of a cover.

Fig. 4 is a plan view of a cover embodying the invention, and

Fig. 5 is an elevational view of the same.

In the embodiment of the invention shown in the drawings the cover is particularly adapted for a transformer tank of the type 30 illustrated in my copending application Serial No. 386,115, filed June 2, 1920. In the formation of the cover a rectangular blank 10 of sheet steel is cut into circular form 11 (Fig. 1) and then has one or more segmental 35 portions 12 cut out of it from the circular edge to a point 13 spaced from the center. The flat disk is then arched or crowned, as by rolling for instance, till its form is convex on the exterior surface and concave on the 40 interior surface and the edges of the cut 12 are brought together (Fig. 3). These edges are then clamped and tightly welded to retain the cover in arched form. This arched form strengthens and rigidifies the structure 45 and gives a pleasing crowned appearance to the transformer tank and also acts to shed rain and moisture. The crowning produced by the method of this invention gives an arch to the cover in all directions symmetrical about the axis of the tank and also symmetrical with relation to both the longitudinal and transverse axis of the cover in case the latter is oblong or oval in form.

After this arching of the cover the center 55 is then cut out for the circular man-hole 15

and holes 16 are also cut for the ends of the transformer lifting rods and holes 17 for the high tension leads. The rectangular opening 20 is also cut for the slab supporting the low tension leads and all of these openings are 60 provided with flanged extensions 21, 22, 23, 24, as shown, to serve as fastening means for bushings or parts covering the openings. These extensions are preferably welded in place and the edges of the opening 12 are 65 also completely closed and welded at 25.

The edge of the cover has holes 26 for the clamp bolts fastening the cover onto the transformer tank body. Extensions 30 may be welded in place overhanging the edge of 70 cover and having openings 31 for upper ends of the lifting rods from the base on which the transformer tank sets. In assembled position the transformer frame rods passing through openings 16 have nuts turned to 75 press upward on the under side of said cover so that the higher central portions of the cover are pressed upward while the lower edge portions are held downward by the clamping to the tank body. The cupped or 80 crowned shape of the cover adapts it to these stresses and also gives a strong arched shape and acts to shed moisture and rain.

The cover of this invention being of sheet steel is light in weight, and the method of 85 formation by cutting from stock sheets is inexpensive and easily adapted to a variety of sizes and types of tanks. The finally completed cover while strong is at the same time 90 flexible enough at the edges to accommodate itself to the top rim of the tank body.

While this invention has been illustrated in connection with a circular tank, it is adaptable also to tanks of other shapes, such as oval or angular, and the invention is 95 not confined to the specific embodiment shown, but is intended to cover such modifications thereof as come within the scope of the following claims.

I claim:

1. A transformer tank cover comprising an integral plate of sheet steel of comparatively shallow dish shape having the interior surface concave and the exterior surface convex giving an arched form to the body 105 portion of the cover in all directions, and having the edges flexible for adapting the under surface to fit the top rim of the transformer tank.

2. A transformer tank cover comprising 110

22
an integral plate of sheet steel having a segmental portion cut out and the edges of the cut welded together and having the interior surface concave and the exterior surface convex giving an arched form to the body portion of the cover in all directions, and having the edges flexible for adapting the under surface to fit the top rim of the transformer tank, the radial depth of the segmental portion being less than the radial depth of the cover at that point.

3. A transformer tank cover comprising an integral plate of sheet steel having a central opening cut in the sheet and a flanged extension fastened thereto, and having a segmental portion cut out to a radial depth terminating short of said central

opening and the edges of the cut welded together, the main body portion of the cover being of arched form in all directions having its interior surface concave and exterior surface convex, and having the edges flexible for adapting the under surface to fit the top rim of the transformer tank.

4. The method of forming a transformer tank cover from a steel sheet, comprising cutting a segment therefrom, bending the body portion of the sheet to give the interior surface a concave and the exterior surface a convex arched form in all directions and forcing the edges of the cut together, and fastening said edges together.

ROBERT V. BINGAY.
